(57) **CLAIM**

The ornamental design for a vending machine cabinet, as shown and described.

DESCRIPTION

FIG. 1 is a front, right, top perspective view of a vending machine cabinet showing new design;

FIG. 2 is a front view of the invention illustrated in FIG. 1; FIG. 3 is a rear view of the invention illustrated in FIG. 1; FIG. 4 is a right side view of the invention illustrated in FIG. 1;

FIG. 5 is a left side view of the invention illustrated in FIG. 1;

FIG. 6 is a top view of the invention illustrated in FIG. 1; and,

FIG. 7 is a bottom view of the invention illustrated in FIG. 1.

The broken lines in the drawings depict environment, or portions, of the vending machine cabinet that are not part of the claimed design.
